UNITED STATES PATENT OFFICE

2,284,377

TUBE FORMING MACHINE

Clarence L. Dewey and Sydney L. Dewey, Cleveland, Ohio, assignors to Metal Tube Shaping Corporation, Elkhart, Ind., a corporation of Indiana

Continuation of application Serial No. 91,468, July 20, 1936. This application November 24, 1939, Serial No. 305,817

4 Claims. (Cl. 113—53)

The machine of the present invention is intended for use in connection with the forming of cylindrical tubing in such a way as to produce any desired degree of taper or to produce grooves, flares, or other circumferential configurations in conformity with a template or master pattern which determines the configuration to be applied to the completed tube. The tubes formed by the present machine are intended for numerous uses such as spindles or legs for furniture, standards for display stands, tapered tubing for use in connection with the manufacture of musical instruments or the like, and many other uses of a like character.

The machine includes means for rotating a tube and providing for its elongation during the forming operation; to the means provided for confining the metal of the tube at the spinning point in such a way as to prevent bulging or distortion; to the means provided for clamping and holding the tube; to the means provided for imparting rotation to the tube and advancing the forming tool, and to the means provided for regulating the thrust of the forming tool in conformity with the configuration of the template or master pattern to impart the desired configuration to the tube.

Further objects and details will appear from the description of the invention in conjunction with the accompanying drawings, wherein,

Figure 1 is a longitudinal sectional elevation of the machine;

Fig. 2 is a cross sectional elevation taken on line 2 of Fig. 1;

Fig. 3 is a cross sectional elevation taken on line 3 of Fig. 1;

Fig. 4 is a face view of a portion of the carriage which supports the tube immediately adjacent the forming point; and

Fig. 5 is a view of the toggle clamp for engaging the tube in such a way as to permit longitudinal slippage thereof during the forming operation.

The machine as a whole is mounted upon side rails 10 of I beam formation, the top flanges of which afford tracks for the contact of upper rollers 11 and lower rollers 12, which are journaled upon the side plates 13 of a carriage 14 having journal bearings 15 which serve to journal a shaft 16 having mounted thereon a pulley 17 and carrying at its inner end a chuck 18 adapted to engage and clamp the end of the tube 19 which is being worked upon. The pulley 17, as shown, is provided with V-shaped grooves 20 which receive pulley belts 21 carried upon a driv-

ing pulley 22 which is slidably splined upon a drive shaft 23 which affords a source of power for the rotation of the tube.

At the opposite end of the machine are located standards 24 which carry journal mountings 25 which serve to journal the reduced end 26 of a shaft 27 carrying a chuck member 28 at its inner end. The reduced shaft 26 carries a grooved pulley 29 driven by belts 30 mounted upon a drive pulley 31 fixedly located upon the shaft 23. The chuck member 28 serves to mount the opposite end of the tube being worked upon. Between the chucks is located a carriage 32 mounted upon upper and lower rollers 33 and 34, which ride upon the track afforded by the upper flanges of the I beams 10.

The carriage 32 at one end has mounted thereon a pair of spaced vertical standards 35, each of which on its inner side is provided with a fin 36 which furnishes a guide for the vertical movement of a former mounting plate 37 which is provided with a pair of depending studs 38 encircled by coil springs 39 bearing upon a bridge plate 40 which connects the lower ends of the standards 35. The lower ends of the studs 38 are entered through apertures in the bridge plate 40, so that the former mounting plate can be moved vertically against the tension of the springs 39.

30 The former mounting plate 37 at its upper end is provided with brackets 41 which carry a pin 42 having mounted thereon a roller 43 which is held by the upward thrust of the springs 39 into contact with the lower edge of a template or master pattern 44 having the configuration which it is desired to impart to the tube. The template is mounted within a groove afforded by side bars 45 and an intermediate center bar 46 of lesser depth, which guide bars are held together by cross bolts 47, and in conjunction furnish a track for a roller 48 carried at the end of an overhanging arm 49 mounted upon one of the standards. This furnishes a roller guide for the carriage 32 and the parts upstanding therefrom.

45 The former mounting plate 37 is provided in its center with an aperture 50 which is rabbeted on the side 51 to afford a socket for a former tool 52 of arcuate semi-circular formation having in its lower straight edge an arch-shaped notch 53 which is rounded to a blunt wedge in section. This arch-shaped edge constitutes the forming surface and has a curvature somewhat greater in radius than the undiminished curvature of the tube being formed. By reason of this configuration, the acting edge of the former tool

will at all times occupy a more or less divergent relation to the surface of the tube, but such divergence will be within such limits as to provide the necessary confinement for the tube at the forming point to prevent the metal from being circumferentially displaced or crowded ahead of the former tool 52 during the spinning operation. In short, the metal will be confined and the tube will be compelled to evenly diminish in diameter when rotated and when the former tool is pressed inwardly by the impulsion afforded by the template.

Immediately in front of the former mounting plate is located a face plate 54 which is also carried by the carriage 32, and this plate has mounted therein the hub 55 of a recessed pulley 64 which surrounds a bushing 56 in contact with the tube. The hub 55 is carried by ball bearings 57 to reduce friction, and the arrangement shown serves to support and center the tube and to provide the necessary confinement thereof at a point immediately in advance of the forming point.

In front of the face plate is located a clamp consisting of semi-circular shoes 58 having friction linings 59 which engage the surface of the tube with sufficient force to assist in its rotation but at the same time permit the longitudinal slippage required in permitting the advance of the former tool longitudinally of the tube. The shoes 58 are each provided with a pair of ears 60 which have pivoted thereto the inner ends of links 61, the outer ends of which are pivoted to lugs 62 inwardly projecting from a plate 63 which is mounted within the recessed pulley 64 having a V-shaped grooves which mount belts 65 driven from a pulley 66 splined and slidable upon the shaft 23. Any suitable or convenient means may be employed for causing the pulleys 64 and 66 to travel longitudinally in unison with one another, and the present illustrations serve merely to indicate a convenient means for imparting power to the elements which rotate the shaft; the same thing is true with respect to the pulleys 17 and 22.

The carriage 32 is fed forward by an endless chain 67 which passes around sprocket wheels 68, one of which is shown at the right of Fig. 1, and suitable means are provided for regulating the feeding speed of the carriage.

Operation

In operation, the tube in its normal or un-tapered condition will be mounted within the machine with its ends clamped within the chucks 18 and 28, and with the carriage 32 and forming tool and friction clutch carried thereby advanced toward the right to the point where the forming operation is to begin. Thereafter, the shaft 23 will be set in operation which will impart rotation to the chucks 18 and 28 and to the friction clamp afforded by the shoes 58 which will be thrust inwardly by toggle action due to the rotation of the pulley 64. With the tube thus clamped and held positively at its ends and by friction at an intermediate point, the forming operation will begin with the advancing of the carriage 32 toward the left and as soon as a projection in the edge of the template is encountered which imparts an inward or radial thrust to the former mounting plate 37, thereby causing the forming tool 52 to press inwardly upon the tube and spin the metal inwardly as the rotation of the tube continues.

The confinement afforded by the arcuate form

of the notch 53 prevents the metal from bulging or being distorted and insures true circularity to the formation irrespective of the depth to which the tool is pressed by the thrust imparted thereon by the template. As the diameter of the tube is reduced, the tube will necessarily be elongated and such elongation is permitted by the movement of the carriage 32, which will adjust itself upon the trackway to the degree required to compensate for the elongation of the tube. The tube will be supported within the hub 55 at a point immediately adjacent to the forming point, so that the metal of the tube will be held in firm contact with the former plate and compelled to reduce its diameter to the extent required by the configuration of the template. At the same time the friction clamp permits slippage along the tube as the carriage 32 is advanced, and this action will continue until the design wrought in the surface of the template has been imparted to the tube. The method involved is one which permits the tube to be reduced either by gradually tapering the same or by abrupt transitions affording grooves, rings, or beadlike projections or shoulders in its surface, depending upon the degree and abruptness of the movements imparted to the forming tool by the configuration of the template.

Although the invention has been described with particularity as to detail, it is not the intention to limit the same to the form shown, since modifications thereof may be made without departing from the spirit of the invention.

We claim:

1. In a tube forming machine of the class described, the combination of spaced chuck members mounted for relative longitudinal movement with respect to one another and adapted to engage the ends of a tube, means for imparting rotation to at least one of the chuck members, a carriage intermediate the chuck members and a forming tool carried thereby and mounted thereon in a manner to permit radial movement of the forming tool with respect to the tube, means for imparting longitudinal movements to the carriage to cause the forming tool to move lengthwise of the tube, automatic means for variably regulating the radial position of the tool with respect to the tube to impart variable reductions in the diameter of the tube, and a rotatably driven friction clamp engaging the tube at a point adjacent the forming tool and movable longitudinally with the forming tool.

2. In a tube forming machine of the class described, the combination of spaced chuck members mounted for relative longitudinal movement with respect to one another and adapted to engage the ends of a tube, means for imparting rotation to at least one of the chuck members, a carriage intermediate the chuck members and a forming tool carried thereby and mounted thereon in a manner to permit radial movement of the forming tool with respect to the tube, means for imparting longitudinal movements to the carriage to cause the forming tool to move lengthwise of the tube, a fixedly positioned template having a patterned edge adapted to impart variable radial movements to the tool to cause corresponding variable reductions in the diameter of the tube, and a rotatably driven friction clamp engaging the tube at a point adjacent the forming tool and movable longitudinally with the forming tool.

3. In a tube forming machine of the class described, the combination of spaced chuck mem-

bers, one being fixedly positioned and the other movably mounted with respect thereto, means for imparting rotation to at least one of the chuck members for engaging and rotating the opposite ends of a tube, a carriage mounted for longitudinal travel between the chuck members, a standard carried by the carriage, a forming tool and a mounting therefor slidably mounted within the standard and adapted to permit radial movements of the forming tool with respect to the tube, a template coacting with the tool mounting for imparting movements thereto commensurate with the configuration of the template, and a rotatably driven clutch movable with the carriage and adapted to frictionally engage the tube and to slide thereon.

4. In a tube forming machine of the class described, the combination of spaced chuck members, one being fixedly positioned and the other

movably mounted with respect thereto, means for imparting rotation to at least one of the chuck members for engaging and rotating the opposite ends of a tube, a carriage mounted for longitudinal travel between the chuck members, a standard carried by the carriage, a forming tool and a mounting therefor slidably mounted within the standard and adapted to permit radial movements of the forming tool with respect to the tube, a spring for normally holding the tool mounting in elevated position, a template coacting with the tool mounting for imparting radial movements thereto commensurate with the configuration of the template and against the thrust of the spring, and a rotatably driven clutch movable with the carriage and adapted to frictionally engage the tube and to slide thereon.
